UNITED STATES PATENT OFFICE.

TRUE D. BEAUMONT, OF LOS ANGELES, CALIFORNIA, ASSIGNOR TO LOUIS F. DUCKER,
OF SAN FRANCISCO, CALIFORNIA.

CLOTHES DRIER.

Application filed August 24, 1927. Serial No. 215,175.

This invention resides in the provision of an improved clothes drier which may be efficaciously operated at a low cost to thoroughly dry large quantities of clothes, the 5 drier being simple as to construction, comparatively small and compact, and capable of association with a washing machine in order that it may use the heat escaping from the washing machine to assist in the 10 drying operation.

An object of the invention is to provide a simply constructed and inexpensive clothes drier of the character described which may be easily handled and operated whether 15 used in connection with a washing machine or a heater, said drier being capable of being heated with various types of heaters as well as with washing machines.

A further object of the invention is to provide 20 a clothes drier of the character described which employs no moving parts and which may be efficiently operated with comparatively little heat.

With the above mentioned and other objects in view, the invention consists in the novel construction and combination of parts hereinafter described, illustrated in the accompanying drawing; and set forth in the 25 claims hereto appended, it being understood 30 that various changes in the form, proportion, size and minor details of construction within the scope of the claims may be resorted to without departing from the spirit or sacrificing any of the advantages of the invention. 35

Referring to the drawing:

Fig. 1 represents a vertical sectional view of the drier construction in accordance with 40 my invention and as it would appear when operated in conjunction with a washing machine.

Fig. 2 represents a cross sectional view of the drier taken on the plane of line 2—2 of Fig. 1.

The embodiment of the invention shown in the accompanying drawing is adapted for operation in conjunction with a washing machine generally designated 1 in order that the heat from the washing machine may be 45 used to assist in the drying operation. However, the drier of this invention may be used in connection with any other suitable heating means.

The drier comprises in the present instance 50 a double walled cylindrical body 2, comprising

an inner cylindrical shell 3 which is disposed within and surrounded by an outer cylindrical shell 4, there being an air space 5 between said shells. At the upper end of the body an annular and angularly formed 60 member 6 is soldered to the upper edges of the inner and outer shells so as to seal the upper end of the air space. The outer shell 4 extends above the inner shell 3 and the angular piece 6 which is substantially L-shaped 65 serves as a support for a removable annular member 7 having cross bars 8 on which clothes may be hung.

The outer shell 4 extends below the lower edge of the inner shell 3 and is adapted to 70 extend into the upper end of a washing machine or wash boiler. An annular rib 12 is provided on the outer shell 4 and engages the upper edge of the washing machine or 75 boiler to limit the inward extension of said shell and to provide for supporting the drier upon the washing machine. The space 80 interiorly of the shell 3, or in other words interiorly of the drier, is closed by a bottom wall 13 mounted in any suitable manner 85 within the lower part of the shell 3 and at a point spaced upwardly from the lower edge of the shell thereby forming a heat retaining compartment or space 14 between the bottom member 13 and lower edge of said inner shell. The hot air and steam is thereby 90 prevented from entering the drying chamber or space but said space is heated by the hot air and steam arising from the washing machine inasmuch as said hot air and steam will pass upwardly into the annular space 5.

A plurality of upwardly and inwardly extending intake tubes 17 are provided near the lower end of the drier at a point above the 95 bead 12, said tubes communicating with openings 18 in the lower part of the drying chamber and with similar openings 19 in the outer shell 4. These tubes in extending transversely across the hot air space 5 become heated by the hot air and steam. Atmospheric air passing through said tubes into said drying chamber is thereby heated. The open upper end of the inner cylinder 100 3 induces a draft of atmospheric air through the tubes and drier.

A heating tube 20 is mounted on the bottom wall 13 in the center thereof and extends upwardly through the drying compartment to the upper end of the latter. 110

This tube extends through an opening 21 in the center of the wall 13 and on its lower open end is provided with an annular lateral flange 22 which is soldered or otherwise secured to the bottom wall. The upper end of the tube is closed. The hot air and steam will pass upwardly into the tube and heat it so that heat will radiate therefrom into the drying compartment. By using this tube the efficiency of the drier is increased inasmuch as there is provided a greater heating surface which will radiate drying heat throughout the drying compartment.

In practice clothes may be either hung from the cross arms 8 into the drying compartment around the tube or otherwise placed in the compartment. The heat radiated from the tube and from the wall of the inner shell 3 will quickly dry the clothes together with the heated atmospheric air which is drawn in through the tube 17, and circulates up through the drying compartment.

The drier of this invention is of simple and inexpensive construction and may be easily handled and operated. By incorporating it with the washing machine, comparatively little space is taken up by the drier and by using the waste heat from the washer, the drier may be inexpensively operated.

A tray as shown at 23, or a plurality of such trays may be used to support the clothes in the drier.

35 I claim:

1. A clothes drier comprising a double walled body having an annular air space between the walls, which air space is closed at the upper end of the drier and open at the lower end, a bottom wall closing the lower end of the drier except the annular space between the walls, said walls having intake openings therein and tubes extending transversely across said annular air space and connected with said openings to provide for induction of atmospheric air into the drier.

2. A clothes drier comprising a body consisting of an outer shell, an inner shell

mounted within and spaced circumferentially from the outer shell providing an annular space between the shells, a wall closing the upper end of said space, the lower end of said space being open, said outer shell extending below the plane of the lower end of the inner shell, intake openings in the inner and outer shells adjacent the lower ends thereof, tubes extending across the air space and communicating said intake openings to provide for conducting atmospheric air into the inner shell and a bottom wall closing the lower end of the inner shell.

3. A clothes drier comprising a body consisting of an outer shell, an inner shell mounted within and spaced circumferentially from the outer shell providing an annular space between the shells, a wall closing the upper end of said space, the lower end of said space being open, said outer shell extending below the plane of the lower end of the inner shell, intake openings in the inner and outer shells adjacent the lower ends thereof, tubes extending across the air space and communicating said intake openings to provide for conducting atmospheric air into the inner shell, a bottom wall closing the lower end of the inner shell and a drying rack supported on the first named wall and extending across the upper end of said inner shell.

4. A clothes drier comprising a double walled body having an annular air space between the walls, which air space is closed at the upper end of the drier and open at the lower end, a bottom wall closing the lower end of the drier except the annular space between the walls, said walls having intake openings therein and tubes extending transversely across said annular air space and connected with said openings to provide for induction of atmospheric air into the drier and a heating tube carried by the bottom wall and extending upwardly within the drier, which tube is open on its lower end and closed on its upper end, there being an opening in said wall through which the open end of the tube extends.

TRUE D. BEAUMONT.
